(57) **CLAIM**

The ornamental design for a sternal closure device with dual locking mechanism, as shown and described.

DESCRIPTION

FIG. 1 is a top perspective view of the claimed sternal closure device with dual locking mechanism with double legs.

FIG. 2 is a top view of the sternal closure device of FIG. 1. FIG. 3 is a side view of the sternal closure device of FIG. 1; and,

FIG. 4 is a first end view of the sternal closure device of FIG. 1.

The dashed broken lines shown in FIG. 4 are included for the purpose of illustrating portions of the sternal closure device with dual locking mechanism and form no part of the claimed design.

1 Claim, 2 Drawing Sheets
